UNITED STATES PATENT OFFICE.

WILLIAM E. SMITH, OF LYNN, MASSACHUSETTS.

TALKING MACHINE.

Application filed January 20, 1920. Serial No. 352,755.

To all whom it may concern:

Be it known that I, WILLIAM E. SMITH, a citizen of the United States, residing at Lynn, county of Essex, State of Massachusetts, have invented an Improvement in Talking Machines, of which the following description, in connection with the accompanying drawing, is a specification, like characters on the drawing representing like parts.

This invention relates to talking picture machines and has for its object to provide a machine of this type having novel sound reproducing elements which will permit of continuous reproduction of sound for an indefinite period, and otherwise to improve machines of this type, all as will be more fully hereinafter set forth.

In order to give an understanding of the invention, I have illustrated in the drawings a selected embodiment thereof which will now be described, after which the novel features will be pointed out in the appended claims.

Fig. 1 is a plan view of the sound-reproducing element;

Fig. 2 is a front view thereof.

The sound-reproducing element is of the phonograph type, it having a sound record, a sound box provided with a needle which co-operates with the record for reproducing the sound, and an amplifying horn. The sound record may be of any suitable type, but I have herein chosen to illustrate a record of the cylinder type.

In order to provide a sound-reproducing element capable of reproducing sound continuously for an indefinite period of time, I propose to make said element in the nature of a duplex element, that is, one capable of holding two sound records, and I propose to arrange said elements so that while the sound is being reproduced from one record, another record may be inserted into the machine so that as soon as the first-named record is finished, the second record may be set into operation. I also provide means whereby when any one record is completed, the device will be automatically switched onto another record, so that the reproduction of the sound will be continuous.

In the device herein shown the sound-reproducing element comprises a frame 4 in which is supported a shaft 5 carrying two drums 6 and 7 on which cylinder sound records 8 and 9 may be placed. Each drum

is provided at one end with a shoulder 10 against which one end of the sound record abuts, and each sound record is held in place on the drum by a clamping nut 11. I will 60 preferably provide both the drum and the nut with intermittent screw-threads after the manner of a breech-lock, so that each nut can be quickly placed into position and then tightened by giving it a partial turn. 65 Each drum has associated therewith a sound box of any appropriate or suitable construction, these sound boxes being indicated at 12 and 13, respectively. Each sound box is provided with a needle 14 which engages 70 the record as usual in phonographs and is constructed so that the vibrations of the needle cause variations or undulations in an electric current in a circuit connected to said sound box. This circuit is in turn connected to a suitable receiver somewhat on the order of a telephone receiver.

Each sound box is carried by a yoke 15 which spans the corresponding cylinder, and each yoke is provided at one end with 80 a hub 16 which is slidably mounted on a supporting rod 17 and at the other end with a half-nut 18 adapted to engage a feed screw 19. The feed screw 19 thus operates to feed the yoke 15 and the sound box sustained thereby in a direction longitudinally of the cylindrical record. The drums 6 and 7 and the feed screw 19 are positively driven by a mechanism operating in timed relation with a moving picture element, and 90 to accomplish this I propose to mechanically connect said drums and feed screw 19 to the moving picture element.

In the construction herein shown each drum has a gear wheel 20 rigid therewith which meshes with and is driven by a gear wheel 21 on a shaft 22. Said shaft has a worm gear 23 thereon meshing with a worm 24 carried by a driving shaft 25 which is connected to a suitable moving picture machine so that the drums 6 and 7 will be rotated positively in timed relation with the moving-picture machine and will thus be kept in perfect synchronism. The feed screws 19 are provided with gears 60 which mesh with and are driven by the gears 21 and thus the feed screws are also kept in perfect synchronism with the moving-picture machine.

As stated above, I have provided means 110 whereby when one of the two records is in use, the sound box for the other record

will be held out of operation, but when the record in use becomes exhausted, the other record will be automatically switched into operation so that the sound will be produced continuously.

The mechanism I have herein shown for this purpose is best illustrated in Figs. 1 and 2. Each of the yokes 15 is provided with an extension 29 which overlies a lifting bar 30 extending parallel to the feed screw 19. Situated beneath each lifting bar 30 are two lifting cams 31, 32 that are pivoted to the frame at 33. When these cams are in their lowered position, as shown at the right, Fig. 2, the lifting bar 30 is in a position out of contact with the extension 29 when the half-nut 18 is resting on the feed screw 19, and when the cams are in their elevated position, as shown at the left, Fig. 2, the lifting bar 30 is raised and by its engagement with the extension 29 will disengage the nut 18 from the feed screw 19. When, therefore, the cams 31, 32 are elevated, the corresponding yoke will be raised, thus lifting its sound box out of engagement with the record, while when the cams are in their lowered position the sound box is dropped into engagement with the record. The two sets of cams are interconnected in such a way that when one set of cams is raised the other is lowered and vice versa. In Fig. 2 the right hand set of cams are lowered, and, therefore, the right-hand sound box is in operative engagement with its record 9, and the left-hand cams are raised so that the left-hand sound box is inoperative. The construction is such that the feeding movement of the sound boxes is from the inner to the outer end of each drum and, therefore, the sound box 13 is moving in towards the right. When said sound box 13 reaches the outer end of the drum, the cams 31, 32 at the left-hand end will be automatically lowered so that the sound box 12 will be dropped into operative engagement with the record 8. For this purpose the two cams 31, 32 for each sound box are connected by a link 34, and each cam 31 is connected by another link 35 to a trip lever 36 pivoted to the frame at 37 and situated adjacent the outer end of the drum at the other end of the frame. Each trip lever is positioned so that it will be engaged by the extension 29 when the sound box reaches the outer end of the record, and therefore when the sound box 13 reaches the end of the record 9, the extension 29 for such sound box will operate to turn the lever 36 at the right hand end of the frame, thus acting through the link 35 to swing the cams at the left hand end from their raised to their lowered position. Thus when the sound box 13 reaches the end of the record, the cams 31, 32 for the other sound box 12 will be automatically lowered so that the sound box 12 will drop into en-

gagement with the record and the nut 18 therefor will drop into engagement with its feed screw 19.

As soon as either sound box is brought into operation the other sound box is automatically rendered inoperative. For this purpose each cam 31 is connected by a link 38 to a lever 39 pivoted to the frame at 40 and situated adjacent the inner end of the drum at the other end of the machine. Each lever 39 is provided with a hooked end 41 adapted to be engaged by the extension 29, and the construction is such that when one set of cams 31, 32; for instance, those at the right-hand side of the machine, Fig. 2, are in their lowered position, the hook 41 on the lever 39 at the other end of the machine is in its raised position, as shown at the left, Fig. 2. Consequently when the left-hand yoke 15 supporting its sound box 12 is lowered by the lowering of the cams 31, 32, the extension 29 will move down behind the hook 41, and when the yoke for the sound box 12 begins its movement to the left, the extension 29 will engage the hook 41, rock the left-hand lever 39, thereby raising the right-hand cams 31, 32, and elevating the corresponding lifting bar 30 into a position to engage the extension 29 of the right-hand yoke 15, thus disconnecting it from the feed screw and rendering the sound box 13 inoperative. The record 9 is thus automatically thrown into operation and the record 8 automatically thrown out of operation, and I propose to make the records so that this shifting from one record to the other will be accomplished without any interruption in the production of sound.

Each yoke is acted upon by a return spring which automatically returns it to its innermost position as soon as it is disconnected from the feed screw. These return springs may have any suitable construction and are connected to drums 43 which are rotatably mounted on the frame and about which are wound flexible bands 44 that are connected to the yokes 15. The movement of each yoke from the center of the machine toward the outer end will wind up the corresponding spring and as soon as the yoke is disconnected from the feed screw, the spring will automatically return it to the innermost position ready to be connected to the feed screw again.

Each record when exhausted may be removed from its drum and replaced by a fresh record while the other record is in operation, and because of this automatic shifting from one record to another, a continuous reproduction of sound is assured for an indefinite period.

In order that a fresh record which is placed into the machine may be in proper synchronism with the moving-picture element, it is necessary that it should not only

be driven at the right speed, but also that it should be properly placed on the drum. If it happens that any record is not properly positioned on the drum, then the sound record will be either slightly behind or slightly ahead of the corresponding picture, and to assist in correctly positioning each record, I propose to make each drum with a positioning projection 98 adapted to enter a slot or notch formed in the record. In placing any record on the drum, the operator will always make sure that the positioning projection is properly entered into the notch of the record before tightening the clamping nut 11.

I claim:

1. In a device of the class described, the combination with two holders for holding cylindrical records, of an independent sound box support for each holder, a feed screw for each sound box support, a sound box carried by each support, means actuated by each support when the sound box thereon approaches the end of a record to establish operative connection between the other sound box support and its feed screw.
2. In a device of the class described, the combination with two holders for holding cylindrical records, of an independent sound box support for each holder, a feed screw for each sound box support, a sound box carried by each support, means actuated by each support when the sound box thereon approaches the end of a record to establish operative connection between the other sound box support and its feed screw, and means actuated by said other sound box

support as it begins its feeding movement to disconnect the first-named sound box support from its feed screw. 40

3. In a device of the class described, the combination with two record holders for holding cylindrical records, of an independent sound box support for each holder, a feed screw for each sound box support, a sound box carried by each support, means actuated by each support when the sound box thereon approaches the end of a record to lower the support for the other sound box to bring it into operative engagement 50 with its feed screw and to bring said other sound box into operative engagement with its record.

4. In a device of the class described, the combination with two record holders for holding cylindrical holders, of an independent sound box support for each holder, a feed screw for each sound box support, a sound box carried by each support, means actuated by each support when the sound box thereon approaches the end of a record to lower the support for the other sound box to bring it into operative engagement with its feed screw and to bring said other sound box into operative engagement with 60 its record, and means actuated by said other sound box support as it begins its feeding movement to raise the first-named sound box support out of engagement with its feed screw and the first-named sound box 70 out of engagement with its record.

In testimony whereof, I have signed my name to this specification.

WILLIAM E. SMITH.
